UNITED STATES PATENT OFFICE.

ROBERT E. GROTE, OF ST. LOUIS, MISSOURI.

DISPLAY-CARD.

1,388,561.

Specification of Letters Patent. Patented Aug. 23, 1921.

Application filed February 13, 1920. Serial No. 358,438.

To all whom it may concern:

Be it known that I, ROBERT E. GROTE, a citizen of the United States of America, a resident of the city of St. Louis, in the 5 State of Missouri, have invented certain new and useful Improvements in Display-Cards, of which the following is a full, clear, and exact description, reference being had to the accompanying drawings, forming a part of 10 this specification.

This invention relates to improvements in display cards, the object being to produce a very simple and inexpensive means for holding and displaying flexible articles, such as 15 strings of tinsel and the like. My object is to provide a simple means whereby such articles may be attractively displayed and at the same time secured to prevent accidental displacement thereof.

20 Figure I is a front elevation of a display card showing strings of tinsel secured thereto.

Fig. II is a front elevation of the card with the tinsel omitted.

25 Fig. III is a side elevation partly in section.

Fig. IV is a transverse section on line IV-IV, Fig. II.

The display card herein shown is an elongated sheet of flexible cardboard slitted on 30 its longitudinal center at points near its upper end to provide an upright tapering hanger tongue 1 adapted to be deflected from the body of the card to form an upwardly 35 extending hanger for the strings of tinsel. The tinsel is folded at the hanger tongue 1, as shown in Fig. I, and the lower end portions of the suspended tinsel lie near the lower portion of the display card.

40 To secure the ends of the tinsel strings, lower portions of the display card are slit in lines crossing the longitudinal center of the card, so as to form a lower retaining tongue 2 and an intermediate retaining 45 tongue 3 between said lower tongue 2 and the hanger tongue 1. The retaining tongues 2 and 3 are arranged at right angles to the hanger tongue 1, and said retaining tongues 2 and 3 extend across the longitudinal cen-

ter line of the card, so as to overlap central 50 portions of the body of tinsel. It is important to observe that the retaining tongues 2 and 3 extend in opposite directions from opposite sides of the tinsel-receiving space, so as to overlie lower portions of the tinsel 55 and prevent displacement thereof in any direction. The tongue 2 is integrally connected to the one side portion of the display card to prevent horizontal displacement of the tinsel in one direction, and the tongue 3 prevents 60 displacement in the opposite direction.

It will now be understood that the invention herein disclosed lies in a very simple display card having a specific combination and arrangement of tongues which coöperate with each other to prevent displacement of the strings of tinsel, or the like. The tinsel is displayed in a very attractive manner, and it is detachably secured with sufficient firmness by the upright hanger tongue 70 1 and the horizontal retaining tongues 2 and 3. In addition to preventing horizontal displacement in either direction, the tongues 2 and 3 prevent the looped upper portion of 75 the tinsel from being accidentally released from the upright hanger tongue 1.

I claim:

A display card for strings of tinsel, said card comprising an elongated sheet of cardboard slitted near its upper end to provide 80 a flexible upright hanger tongue whereon the strings of tinsel may be folded, said upright hanger tongue being deflected from the body of the cardboard to receive the folded portion of the tinsel, and lower portions of said card being slitted to provide 85 a lower retaining tongue and an intermediate retaining tongue between said lower tongue and the hanger tongue, said retaining tongues being arranged at an angle to 90 said hanger tongue and extended in opposite directions from opposite sides of the tinsel receiving space, so as to overlie lower portions of the tinsel and prevent free displacement thereof in either direction. 95

In testimony that I claim the foregoing I hereunto affix my signature.

ROBERT E. GROTE.
